UNITED STATES PATENT OFFICE

113,687

DESIGN FOR A POCKET MEDICINE CONTAINER

David Sholtz, Miami, Fla., assignor, by mesne assignments, to Thompson's Limited, New York, N. Y., a corporation of New York

Application October 27, 1938, Serial No. 80,717

Term of patent 14 years

To all whom it may concern:

Be it known that I, David Sholtz, a citizen of the United States residing at Miami, in the county of Dade and State of Florida, have invented a new, original, and ornamental design for a Pocket Medicine Container, of which the following is a specification, reference being had to the accompanying drawing, forming part thereof.

In the drawing:

I claim:

The ornamental design for a pocket medicine container, as shown.

DAVID SHOLTZ.
